BEVERAGE COOLER

Duffy A. Matot, Wilmette, Ill.

Application July 8, 1938, Serial No. 218,089

3 Claims. (Cl. 312—140.1)

This invention relates to improvements in a beverage cooler or refrigerator containing packages or casks and is more particularly directed to a type arranged for compactness, while having the bar proper unobstructed, and with means for facilitating the insertion and withdrawal of the package or cask from which the beverage is directly dispensed.

In the construction of bars and back-bars of various types, due to the large space which they occupy, the bars are usually set relatively close to the back-bar, permitting in some instances approximately 30 inches between them. It has been a very difficult task to insert packages or casks into beverage coolers due to the small space permitted between the bar and back-bar, and when lifted into position, it was impossible to hold on to the package, therefore, it would drop into position in the cooler and cause the water therein to splash and the weight of the package damaging the cooler. And it is to overcome these objections that the invention appertains.

In my improved beverage cooler, I employ horizontally swingable doors which may be opened substantially aligned and flat with the cooler and a rocking and supporting means pivotally carried on the sill of the door whereby the rocking and supporting means may be swung to receiving or inserting position in a substantially vertical plane and to require relatively small space for its swinging movement.

The chief objects of the present invention are the provision of a beverage cooler which is simple in construction, compact, strong and durable, and having compartments which closely surround the packages or casks thereby requiring a lesser area to be cooled by the refrigeration contained in the cooler.

Another object is the provision of package or cask supporting means permitting of a turning movement of the package or cask to tap the same while in the cooler.

A still further object is the provision of a beverage cooler having compartments with their top walls in close proximity with the package or cask and with a doorway of approximately one-half the height of the package or cask permitting of a greater amount of water to be used for refrigeration and through which doorway, the package is inserted and with rocking and supporting means for facilitating the inversion of the package or cask.

Another object is the provision of a cooler

wherein the faucets are tapped directly to the packages or casks without the use of coils.

And a further object is the provision of a package or cask rest permitting the package or cask to be partially inserted and retained in that position in the cooler while tapping packages or casks having bung openings positioned centrally thereof. When tapped, it is only necessary to tilt the package or cask slightly forward to release the rest and permit the package or cask to be positioned in the cooler.

Referring to the drawing:

Figure 1 is a perspective view of my improved beverage cooler, illustrating in dotted lines the position a package or cask will occupy in the initial step of placing it in one of the compartments of the cooler.

Figure 2 is a vertical sectional view taken substantially on the line 2—2 of Figure 1, showing the package or cask in dotted lines and the door 20 of the compartment closed.

Figure 3 is a partial plan sectional view taken substantially on the line 3—3 of Figure 2.

Figure 4 is a detail view in side elevation of the rest for limiting the movement of the package or cask, and for holding the same in tilted position while tapping.

Figure 5 is a detail perspective view of a modified form of rocking and supporting means having the package or cask rest carried thereby.

The reference numeral 10 designates the cooler or refrigerator as a whole, which, as shown, is provided at each of its ends with a compartment 11 which extends vertically from the floor to the top 12 of the cooler. The front wall 13 of the cooler extends vertically from the floor to the top 12 of the cooler, while what may be termed as the rear wall 14 of the cooler extends a substantially lesser distance, having hingedly fixed thereto, a pair of doors 15 and 16, respectively, that inclose the compartments 11. Interposed between the compartments is a cooling chamber 17 which is arranged to receive ice or other cooling medium, and which is separated from the compartments 11 by a wire mesh 18 on each side thereof. This mesh 18 serves to retain the ice in the cooling chamber 17 while permitting the water to flow outwardly on each side thereof into the compartments. Above the doors 15 and 16, the cooler is provided with L-shaped portions 19 and 20, respectively, which serve as drainboards 21 and 22, respectively, and on which drainboards drinking glasses may be placed out of sight of the patron, and which boards are inclined to direct the water to a center drain 23 positioned in

the top portion of the cooling chamber 17. Above this cooling chamber 17 and fixed to the rear portion of the top of the cooler 12 is a plate 24 to which a pair of faucets 25 are secured and each of which faucets are directly connected to a beverage package or cask 26 (shown in dotted lines Figs. 1, 2 and 3).

As thus far described, it will be noted that when viewed in side elevation, the cooler is somewhat of L-shaped formation having the top of the cooler 12 forming the bar proper and the drainboards 21 and 22 of the L-shaped portions 19 and 20 positioned between the top of the cooler 12, and the doors 15 and 16 serving with the top 12 of the cooler to inclose the compartments. The L-shaped formation of the drainboards serves to reduce the size of the compartments 11, which is a favorable condition requiring the least amount of refrigeration to cool the same while the drainboards also serve as rests on which the drinking glasses are placed out of sight of the patrons and are readily accessible.

As the compartments are each identical in construction, it is thought that a description of one will suffice for a description of all.

In order to insert a package or cask 26, it is only necessary to remove a small face plate 24a positioned over the cooling chamber 17 and to open the door, as for example Fig. 1, and to then remove the L-shaped portion 19 which gives the operator access to the interior of the compartment 11. The rocking and supporting means 27 which is normally in the compartment, is then gripped and swung until its top end hook portion 28 contacts and rests on the floor outwardly of the cooler. This rocking and supporting means 27 comprises a rigid bar 27a formed to provide at its top end, a hook portion 28 and at its lower end a right-angled portion 29 and an offset 30 intermediate its length. The bar is secured at 31 to a plate 32 which is provided with brackets 33 into which a pair of oppositely directed fingers 34 enter, and which fingers are secured in the sill 35 of the doorway and serve with brackets 33 to form a hinge for the rocking and supporting means. Adjacent each hook portion 28, the rocking and supporting means 27 is provided with a guide 36 which serves to retain the package or cask in position against rocking movements thereon.

In the operation of inserting a package or cask into the cooler, one of the doors 15 or 16 is swung to open position and the rocking and supporting means 27 is manually swung on its hinge 33-34 until the top end hook portion 28 thereof is in resting position on the floor, and at which time, it is in receiving position for the package or cask. When in this position, the rocking and supporting means 27 is substantially in a vertical position permitting of the easy passage of the package or cask 26 between the cooler 10 and the back-bar (not shown), and also permitting the rolling of the package with the top portion thereof at the bottom, so that it may be easily set over the top hook portion 28 and then tilted slightly until its side engages the bar 27a and the guide 36. This slight movement of the package or cask 26 causes the free end thereof, which in this instance is at the top, to move under the right-angled portion 29 of the bar 27a and it is then only necessary to exert a relatively light upward pull on the package or cask 26 to cause the same to swing with the rocking and supporting means 27 on the hinge 33-34 until the package or cask is inserted in its respective compartment 11.

The insertion of the package or cask 26 inverts the same and its top portion is then exposed to the operator where he may easily tap the package. It will be noted that during the insertion of the package 26, a complete control thereof is had, whereby it may be swung into the water for cooling the same without splashing, as the package is at all times retained between the hook 28 and the right-angled portion 29 of the rocking and supporting means 27.

After the package is in position, it may be easily tapped and pivotally turned while retained by the rocking and supporting means 27. In order to easily turn the package, the floor of each compartment 11 is provided with a plurality of radially directed fixed guide portions 37, and these guide portions serve as rests on which the package or cask 26 is placed when set in position in the cooler. While the package or cask 26 is being manually turned or pivoted in its compartment 11, the lower end thereof is then in contact at three points with the guide members 37 assuring a perfect and steady rest for the package and thereby permitting of the circulation of water around and under the package.

As the rocking and supporting means 27 is pivotally supported on the door sill of the cooler at approximately midway of its length, it is possible to permit of a water line of approximately one-third of the height of the package or cask 26 and thereby assisting in the cooling thereof. Also, it will be noted that in order to insert the package 26, the L-shaped portions 19 or 20 forming the drainboards 21 or 22, must be removed to permit of the swinging movements of the package, and when replaced, these L-shaped portions 19 or 20 will be in close proximity with the top portion of the package, so as to reduce the space above the water line and provide a lesser area to be cooled to retain a given temperature.

When inserting packages or casks having center bungs, provision has been made to facilitate the tapping of the same. The cask 26 is placed on the hook portion 28 in the manner above described, and a rest designated as a whole as 38 is manually moved into position to permit of a given swinging movement of the package or cask so as to retain the same at an angle of approximately 45 degrees to its normal vertical position, whereby the operator may easily tap the package and then complete its insertion into the cooler. The rest 38 comprises a relatively rectangular member 39 pivoted at 40 to the inside face of the front wall 13 of the cooler. Approximately intermediate its length, the member 39 has a member 41 pivoted thereto at 42. This member 41 is of channel formation to embrace the member 39 on three sides and is provided with an integral ear 46. This rest 38 is normally urged in one direction out of the path of movement of the package by a tension spring 44 which has one end secured thereto and its other end secured at 45 to the end wall of the cooler.

In its operation, the rest 38 is manually swung against the tension of the spring 44 to a vertical position and the channel-shaped member 41 is then pulled outwardly to rock on its pivot 42 which carries the integral ear 46 thereof over a pin 43 fixed in the front wall 13 of the cooler. This pin 43 retains the rest 38 in a vertical locked position against the tension of its spring 44 and the member 41 in the path of the lower portion of the package or cask 26, so that, as the package or cask is swung to insert the same into position, the lower edge portion thereof will engage

the member 41 and cause the same to rock on its pivot 42 and carry the ear 46 out of the path of the pin 43. During this time, the friction of the package will retain the rest 38 released, but 5 in position to prevent the package or cask from being fully inserted within the compartment 11. When in this position, the operator may tap the package, and when tapped, the package or cask 26 is then tilted forwardly, slightly away from 10 the rest 38 which permits the spring 44 to urge the rest 38 to normal position out of the path of the package, and at which time, the package may be inserted in the compartment and manually turned or pivoted to a suitable position for 15 aligning the connections for drawing the beverage.

In Figure 5, a modified form of rocking and supporting means 50 is shown in which the right-angled portion 51 at the lower end thereof has a 20 disk 52 pivotally attached thereto at 53. In this construction, the disk 52 is normally over the top of the package when the same is positioned on the rocking and supporting means 50 and when swung into position within the compartment 25 11, the right-angled portion 51 rests on the floor of the cooler and the package then rests on the disk 52 and may be bodily turned or pivoted with the disk on the angled formation 51.

I claim:

1. A beverage cooler of the character described, 30 having a water holding compartment provided with a doorway terminating at a distance above the bottom of the compartment, a door hinged for horizontal movement and closure of said 35 doorway, a rockable package supporting means pivotally mounted in each doorway and having means at its ends for engaging the ends of a package whereby to swing said package from outwardly of the cooler to a vertical position within 40 said cooler, and a rest in the compartment arranged to be manually positioned in the path of movement of the package for holding the package partially inserted, and means coacting with the rest whereby said rest is moved out of the 45

path of the package when the package is rocked away from said rest.

2. In a cooler of the character described having a water holding compartment provided with a doorway terminating at a distance above 5 the bottom of the compartment, a door hinged to the casing of the doorway for horizontal movement and closure of said doorway, a rockable supporting means pivotally mounted on the sill of the doorway, said rockable supporting means 10 having engaging means at each of its ends whereby to engage and retain a package for rocking movements with the rockable supporting means, a rest within said compartment, said rest being pivotally supported and normally spring-urged 15 out of the path of rocking movements of the package, means on said rest for manually locking the same in the path of movement of said package for holding said package in partially 20 inserted position in the compartment, said means being released when engaged by the package and spring-urged to normal position when the package is slightly rocked away from said means, said means when restored permitting of the insertion 25 of the package within the compartment. 25

3. In a cooler of the character described having a water holding compartment provided with a doorway, a door hinged to the casing of the doorway for horizontal movement and closure of said doorway, a rockable supporting means pivotally mounted on the sill of the doorway, said rockable supporting means having means for engaging the ends of a package, a rest pivotally supported in the compartment and normally 30 spring-urged out of the path of rocking movements of the package, and package engaging lock means on said rest arranged to be normally adjusted to lock the rest in the path of movement of said package, said means being released when engaged by the package and retaining the 40 package in partially inserted position in the compartment, the package when tilted permitting said rest to be spring-urged to normal position for the free insertion of the package. 40 35 45
